DUAL WINDOW STRUCTURE

Robert Hayne, Indian Hill, Ohio

Application February 19, 1938, Serial No. 191,526

8 Claims. (Cl. 20—53)

The present invention relates to basement type windows and has for an object the provision of a dual purpose window that provides for daylight illumination of the ordinarily shadowed area immediately beneath the window.

Another object of the invention is to provide a device of the character that is effective for the aforesaid purpose regardless of whether the window is open for ventilating purposes or closed against inclement weather.

A further object of the invention is to provide a simple means whereby the dual window is held in fully open position or latched in closed position and whereby the structure may be selectively utilized as a daylight deflector when open or closed.

These and other objects are attained by the means described herein and disclosed in the accompanying drawing, in which:

20 Fig. 1 is a vertical sectional view showing a window structure of the invention in a basement wall, showing the window in full line, as arranged for both ventilation and the illumination of the area below the window with deflected outside 25 daylight, the view further showing, in dotted lines, the position of the window when fully opened.

Fig. 2 is a vertical sectional view showing the window as positioned when used as a daylight deflector and a closure against inclement weather.

30 Fig. 3 is an enlarged fragmental front elevational view showing the relationship of a window frame with the dual purpose window sash structure completely closed and latched by the swinging suspension and latch bar forming a detail of the invention.

Fig. 4 is a fragmental view showing the outer sash latched independently of the auxiliary window.

40 Fig. 5 is a perspective view of a swinging suspension bar forming a detail of the invention, part being broken away.

Heretofore it has been common to place household fixtures such as stationary wash tubs, or 45 objects such as work benches directly beneath basement windows and against the basement wall where fresh air can be had, but the area beneath the window is usually very shadowy and dark and an electric light fixture cannot be positioned 50 to good advantage because the window in open position interferes with the most desirable location for a fixture.

By means of the present invention, a window construction of substantially ordinary appearance 55 is provided with means to position the win-

dow members in the usual fully open and fully closed conditions and also in daylight deflecting positions with selective ventilation or closure against inclement weather.

Referring now to the drawing, the device of the 5 invention may be mounted in a basement window frame 10 of any approved construction and bounding the usual window opening in a basement or other wall 11. The window structure comprises an outer window sash 12 hinged at its 10 top in well known fashion by hinges such as 13 upon the top horizontal member of frame 10. Outer sash 12 is of any desired construction and resembles basement sashes now in common use, save that a recess or shoulder 14 which is 15 rabbeted out to afford a seat into which an auxiliary sash 15 fits with its interior face flush with the interior face of sash 12.

The auxiliary sash 15 is hinged at 16 on the sash 12 at the top so that the outer sash 12 20 may remain closed and latched while the auxiliary sash is held at an angle thereto (see Fig. 2). The auxiliary sash is glazed with a window light 17 which may be clear glass. Translucent glass of any description may be employed in lieu of the 25 clear glass 17 if privacy is desired.

The outer sash 12 is glazed with clear glass 18. When the auxiliary window sash or both sashes are held at an angle of the order of 20° from the vertical, a large number of outside light rays are 30 deflected downwardly. There is thus afforded good illumination during the daylight hours in a basement area that is normally very gloomy and shadowed and where visibility is particularly poor because the occupant ordinarily has all of the 35 entering outside light shining directly in his eyes and practically no light on the object disposed in this area. The interiors of laundry trays, and other deep box-like structures are particularly well illuminated by the window structure of the 40 invention because the light is deflected in substantially a vertical downward direction.

It will be noted that the auxiliary sash and the outer sash carry window panes 17 and 18 respectively of uniform size and that the two sashes 45 are capable of occupying the same space as one ordinary basement sash when wooden construction is employed. The structure is not limited to the use of wood since the same relationship of parts may be attained in metal construction. 50

The simple suspension and latching means for controlling the window structure is preferably formed of strip metal stampings. The parts consist of suspension bar 19 having a pair of eye slots 20 in the top end 21 thereof, which end is turned 55

at an angle of 90° to the body of the bar. A plate 22 has a pair of perforated tongues 23 struck therefrom and disposed in substantially parallel forwardly extending spaced relation so that the perforate end 21 may be loosely suspended on a pintle or bolt 24 passing through said perforate tongues 23 and the endmost eye 20 of the bar. Screws 25 are used to mount hinge plate 22 to the top horizontal member of window frame 10 so as to provide a pivot point for bar 19 at a level above the hinged mounting 13 of the outer window 12. The two sashes together may thus be fully raised to a horizontal position, or substantially so, without engaging the hinged mounting of the bar 19. The bar thus suspended hangs down, entirely across both window sashes and across the bottom sill of the window frame 10.

On the bottom member of frame 10 is secured, as by screws 26, a latch mounting plate 27 which has pivoted thereon at 28 a latch 29 that normally rests in a horizontal position on a lug 30 which is struck from the body of plate 27. One end 31 of latch 29 is bent slightly forward to form a cam surface which may ride smoothly onto the forward face of a catch plate 32 which is mounted on the lower member of outer sash 12 just above the plate 27. As is best illustrated, latch 28 may be turned on its pivot to effectively latch the outer sash, leaving the suspension bar and the auxiliary sash free for independent adjustment. The righthand portion of latch 29 is offset as at 33 so that the portion 34 is spaced from the latch mounting plate 27 at a distance to permit the thickness of suspension bar 19 to pass snugly beneath it as shown in Fig. 3. The suspension bar, when thus latched in the keeper portion 34, precludes inward movement of both sashes. The sashes each have a catch member which snugly embraces the suspension bar, as hereinafter described, so that both sashes are held solidly to prevent rattling as well as against opening from the outside. Suspension bar 19 has a pair of spaced hooks 35 and 36 which may be struck from the body of the bar or they may be otherwise formed and attached thereto.

Catch plate 32 has an integral catch member 37 struck therefrom and spaced away from the plate so as to ride on top of hook 35 when the parts are in the position shown in Fig. 3. A notch 38 is cut in the lower edge of catch member 37.

Auxiliary sash 15 has a catch plate 39 secured thereto, said plate providing a catch 40 with a notch 41. The hook 36 on the suspension bar 19 cooperates with catch 40 in the same manner as do the hook 35 and catch 37.

The notched catches 37 and 40 cooperate with hooks 35 and 36 on the suspension bar in the following several ways for attaining different conditions in the basement.

During inclement weather the user may latch the outer sash 12 in closed condition (see Fig. 2) by angularly adjusting latch 29 onto catch plate 32 and then engaging catch 40 on hook 36 of the suspension bar 19 in order to attain a maximum downward deflection of daylight that passes through the clear glass 18 in the outer window 12. As shown by the dashed arrows, the auxiliary glass 17 will pass some of the light and deflect some of the light downwardly to dispel the shadow and gloomy appearance that normally exists beneath such windows.

When the advantage of the deflected light is not required, both sashes may be securely latched

in position as shown in Fig. 3 and the structure acts as a double window to reduce heat losses.

If outside ventilation through the window is wanted in conjunction with the advantage of the deflected outside daylight, catch 37 on sash 12 is engaged on hook 35 thereby supporting the outer window at an angle for maximum downward deflection of the light from the glass 18. The auxiliary sash merely rests on top of the outer window at this time (see Fig. 1).

When the daylight deflection is unimportant but the window is wanted wide open, the catch 37 is engaged on hook 36 thus suspending both sashes in raised position as shown in dotted lines in Fig. 1. The pivotal mounting on pintle 24 is shifted to the second slotted eye 20 to make this adjustment.

The end of suspension bar 19 is hook-shaped at 42 to facilitate lateral swinging thereof to engage and disengage the bar with the various co-operating parts hereinbefore described. It is to be noted that notches 38 and 41 preclude accidental displacement of hooks 35 and 36 from the catches.

The operation of the device is simple and adjustments to attain desired control of light, air, and temperature are quickly made.

What is claimed is:

1. The combination with a basement window frame, of an outer sash hingedly mounted at its top to said frame, an auxiliary window hingedly mounted at its top to the top of the outer sash, and suspension means to selectively suspend the sashes at an angle such that outside light is deflected substantially vertically downwardly below the window.

2. The combination with a basement window frame, of an outer sash hingedly mounted at its top to said frame, an auxiliary window hingedly mounted at its top to the top of the outer sash, suspension means to selectively suspend the sashes at an angle such that outside light is deflected downwardly below the window, and latch means on the window frame selectively engageable on the outer window and said suspension means for latching the outer window or both windows in closed position.

3. The combination with a basement window frame, of an outer glazed sash hinged to the frame controlling the opening in the frame, a pivoted latch on the frame opposite the hinged mounting of said sash for latching said sash in closed position, an auxiliary glazed sash hinged to and nestable within the body lines of said outer sash, and suspension bar means pivoted to the frame above said outer sash for selectively holding said auxiliary sash and the outer sash at approximately a predetermined angle to the vertical wherein outside light is deflected substantially vertically downwardly below the window frame.

4. In a device of the class described the combination of a suspension bar adapted for swinging and pivotal mounting above a basement window, hooks on said bar disposed at different distances from said mounting, and a catch adapted for fastening to the free edge of a top hinged sash of the basement window for selective engagement with said hooks whereby the sash is positioned at an angle of the order of twenty degrees from the vertical for deflecting substantially vertically downwardly the outside light rays which enter the window and for positioning said sash clear of the window opening and in approximately horizontal position.

5. In a dual purpose window control the combination of a suspension bar having hooks spaced longitudinally from an end of the bar, means adapted for wall mounting for pivotally and 5
6. swingingly supporting said bar at the end opposite the hooks, laterally opening catches adapted for mounting on hingedly mounted nestable sashes whereby the inner or both of said sashes are supported at predetermined angular positions by 10
10 engagement of said catches on selected hooks on said bar, and a latch member adapted for selectively engaging said bar and one of said catches for retaining the outer or both of said sashes in closed position. 15
15. 6. A dual window control comprising a suspension bar, means to pivotally and swingably support the bar at one end, hooks spaced longitudinally of the opposite end of said bar, a catch comprising spaced parts adapted to slidably receive the hook and bar between them, one of said parts being notched at the bottom and adapted to be engaged between the bar and either of said hooks, and a pivoted latch adapted in one position to engage said catch, and in an 20
20 other position to slidably receive said bar adjacent said hooks.
7. In combination a suspension bar, means to mount said bar at one end above a basement window, a pivoted latch member for mounting below a basement window and adapted to receive the lower end of said bar, hooks on said bar, and notched catch members adapted for mounting on the lower portions of nestable double sashes, said catches adapted to rest upon 10 said hooks when the suspension bar is engaged by said latch, said hooks being engageable in the notched portions of said catches for holding the sashes selectively in predetermined angular position. 15
8. In combination a double window comprising a frame, a pair of nestable sashes, window lights in said sashes, the outer window light at least being transparent, and cooperating means to selectively suspend the sashes at predetermined angles whereby outside light may be deflected substantially vertically downward from either of the window lights. 20
